UNITED STATES PATENT OFFICE.

JAMES WATSON, OF ADDISON, OHIO.

FEED-CUTTER.

SPECIFICATION forming part of Letters Patent No. 251,146, dated December 20, 1881.

Application filed November 10, 1881. (No model.)

To all whom it may concern:

Be it known that I, JAMES WATSON, of Addison, in the county of Gallia and State of Ohio, have invented certain new and useful Improvements in Feed-Cutters; and I do hereby declare that the following is a full, clear, and exact description of the invention, which will enable others skilled in the art to which it appertains to make and use the same, reference being had to the accompanying drawings, which form a part of this specification.

Figure 1 is a front view of my improved feed-cutter. Fig. 2 is a vertical sectional view. Fig. 3 is a horizontal sectional view taken through the operating-lever. Fig. 4 is a detail view, in perspective, of the upper part of the machine; and Fig. 5 is a perspective view of the fender and fender-guard detached.

Corresponding parts in the several figures are denoted by like letters of reference.

This invention relates to feed-cutters; and it consists in certain improvements in the construction of the same, which will be hereinafter fully described, and particularly pointed out in the claims.

In the drawings hereto annexed, A represents a vertical board or plank, which forms the front end of the box, (not shown,) with which it communicates through an opening, B.

Secured transversely to the lower end of plank A is a cross-piece, C, forming the base.

D D are two guide-strips, having grooves E in their inner and flanges F on their outer sides. At their upper ends the said guides are pro-

vided with suitably-constructed hooks G, as in Fig. 4, by which they are hung or adjusted in notches H at the upper end of plank A, their lower ends being supported upon the base C and secured to plank A by single screws or bolts in such a manner that the said guides and the plank A shall be a slight distance apart, so as to leave room for the operating-lever, as will be hereinafter described. The cross-piece or base C has an upright, I.

J is the operating-lever, which is pivoted to the upper end of a connecting-rod, K, the lower end of which is pivoted to upright I, as shown. The lever J consists of two rods or straps embracing the guide-strips D, connected by a handle, L, and having the knife or cutter M,

which works in the grooves E of the guide-strips, secured between them by a single bolt or pivot, N. The knife or cutter, which is rhomboidal in shape, has its upper and lower edges sharpened, so as to be capable of being reversed when required, being braced in the grooves of the vertical guides and between the rods or strips composing the operating-lever. It may be made of very thin metal without danger of bending or giving. Horizontal guides O, for the lower edge of the knife, are secured transversely to the guides D, as shown.

To regulate the length of the stroke of lever J, I employ an adjustable stud, P, which may be an ordinary wood-screw screwed into one of the guide strips D. As the edge of the cutter becomes worn the said stud may be lowered sufficiently to compensate for such wear.

Q is a strap secured or pivoted to lever J and carrying the fender, which consists of a plate, R, having clamps S embracing the flanges F of guides D, upon which it slides.

T is a guard or plate, adjustable in grooves U in the inner sides of clamps S, in order to regulate the length of the feed to be cut. The fender is secured to strap Q by a bolt, V, in such a manner that it may be raised, when necessary, in order to compensate for wear of the edge of the knife or cutter.

From the foregoing description, taken in connection with the drawings hereto annexed, the operation of my improved feed-cutter will be readily understood. It is simple, inexpensive, convenient, and easily operated.

Having thus described my invention, what I claim, and desire to secure by Letters Patent of the United States, is—

1. The combination of the front board, A, having notches H, base C, and guides D, having hooks G, by which they are hung in notches H and supported on base C, substantially as described.

2. The combination of the front board, A, the guides D, the lever J, consisting of rods or straps embracing said guides, and the knife or cutter M, pivoted and clasped between the rods or straps composing lever J, substantially as set forth.

3. The combination, with the guides D, having flanges F, of the fender R, having grooved

clamps S and adjustable plate T, and the strap Q, connecting said fender to the operating-lever, substantially as set forth.

4. As an improvement in feed cutters, the combination of the front board, A, base C, guides D, having grooves E, flanges F, and hooks G, lever J, consisting of rods or straps embracing the guides D, knife M, clamped and pivoted between the straps composing lever J, and the fender R S, having adjustable guard

T, all arranged and operating substantially as and for the purpose set forth.

In testimony that I claim the foregoing as my own I have hereto affixed my signature in presence of two witnesses.

JAMES WATSON.
